US00D799037S

(12) **United States Design Patent** (10) **Patent No.:** **US D799,037 S**
Kubiak et al. (45) **Date of Patent:** **** Oct. 3, 2017**

(54) **GRID POSITIONING DEVICE**

(71) Applicants: **Erik Noble Kubiak**, Salt Lake City, UT (US); **Jeremy Gililand**, Salt Lake City, UT (US); **Richard Boddington**, Salt Lake City, UT (US); **Edouard Saget**, Salt Lake City, UT (US)

(72) Inventors: **Erik Noble Kubiak**, Salt Lake City, UT (US); **Jeremy Gililand**, Salt Lake City, UT (US); **Richard Boddington**, Salt Lake City, UT (US); **Edouard Saget**, Salt Lake City, UT (US)

(73) Assignee: **Orthogrid Systems, Inc**, Millcreek, UT (US)

(**) Term: **15 Years**

(21) Appl. No.: **29/600,801**

(22) Filed: **Apr. 15, 2017**

Related U.S. Application Data

(62) Division of application No. 29/543,601, filed on Oct. 27, 2015, now Pat. No. Des. 788,300.

CLAIM

The ornamental design for a grid positioning device, as shown and described.

DESCRIPTION

FIG. 1 is an isometric view showing our new design.

FIG. 2 is a front view showing our new design.

FIG. 3 is a right side view showing our new design, the left side being identical.

FIG. 4 is a bottom view showing our new design; and,

FIG. 5 is a top view showing our new design.

The broken lines shown are included for the purpose of illustrating portions of the grid positioning device that form no part of the claim.

1 Claim, 4 Drawing Sheets
